UNITED STATES PATENT OFFICE.

WILLIS B. YOUNG, OF OLYMPIA, WASHINGTON.

ATTACHMENT FOR INTERNAL-COMBUSTION MOTORS.

Application filed March 22, 1922. Serial No. 545,781.

To all whom it may concern:

Be it known that I, WILLIS B. YOUNG, a citizen of the United States, residing at Olympia, in the county of Thurston and State of Washington, have invented new and useful Improvements in Attachments for Internal-Combustion Motors, of which the following is a specification.

This invention relates to certain novel and useful improvements in attachments for internal combustion motors, and has particular application to a device for preventing back fire through the carburetor assembly of the motor.

15 In carrying out the present invention it is my purpose to provide a device whereby back fire through the carburetor assembly of the internal combustion motor will be prevented and the gases incident to the back fire directed to the atmosphere without affecting the carburetor.

It is also my purpose to provide a device of the class described which may be readily and quickly connected in the intake manifold between the carburetor and the motor cylinders and which will operate to automatically cut off communication between the carburetor and the cylinders and automatically establish communication between the intake manifold and the atmosphere in the event of the back firing of the motor, thereby preventing the gases resulting from the back fire passing through the carburetor.

35 A further object of my invention is to provide a device of the character set forth which will embrace the desired features of efficiency, simplicity and durability, which may be readily and quickly connected in the intake manifold of an internal combustion motor between the cylinders and the carburetor and which will embody comparatively few parts, and these so arranged and co-related as to reduce the possibility of derangement to a minimum.

45 With the above recited objects in view and others of a like nature my invention resides in the construction, combination and arrangement of parts set forth in and falling within the scope of the appended claim.

50 In the accompanying drawings:

Figure 1 is a fragmentary side elevation of an internal combustion motor showing my invention connected in the intake manifold between the engine cylinders and the carburetor.

Figure 2 is an enlarged sectional view through my attachment.

Figure 3 is a horizontal sectional view on the line 3—3 of Figure 1.

Figure 4 is a vertical sectional view on the line 4—4 of Figure 1.

Referring now to the drawings in detail, A designates a portion of an internal combustion motor equipped with an intake manifold *a* and a carburetor *b*.

Interposed in the intake manifold between the carburetor and the engine cylinders is my device indicated as an entirety by the reference character B.

In the embodiment of my invention selected for illustrative purposes my device comprises a vertically disposed valve chamber 1 cylindrical in cross section and having the upper end formed with a fastening flange 2 and the lower end formed with a similar flange 3. These flanges 2 and 3 are bolted, or otherwise appropriately secured to the corresponding flanges 2' and 3' on the lower end of the intake manifold *a* and the upper end of the outlet *b* of the carburetor, as clearly illustrated in Figures 1 and 2 of the drawings, the chamber 1 being of the same diameter as the intake manifold and in axial alignment therewith. In the present instance the inner wall of the chamber 1 adjacent to its lower end is formed with an inwardly extending circular flange 4 formed to provide a valve seat 5, and engaging the valve seat 5 is an upwardly opening check valve 6, hinged or pivoted upon a pin 7 having the ends suitably seated in the wall of the chamber 1, as shown in Figure 3. This valve 6 opens upwardly in the operation of the motor so that the combustible mixture may pass from the carburetor through the chamber 1 and the intake manifold to the cylinders of the motor.

In the present form of my invention the chamber 1 above the check valve 6 is formed with an outlet port 8, and integral with the wall of this outlet port and extending therefrom at right angles to the chamber 1 is an outlet tube 9 having its outer end formed with an inturned flange 10 that provides a valve seat 11.

In this form of my invention the outer end of the tube 9 carries a valve chamber 12 of suitable construction and provided with an opening surrounding the corresponding end of the tube 9, the wall of the opening

being formed with a securing flange 13 that embraces the outer end of the tube 9 and is secured in such manner as to hold the chamber 12 securely to the tube.

5 The wall of the chamber 12 opposite from the outer end of the tube 9 is formed with an inwardly extending guide tube 14 in axial alinement with the tube 9, and in this guide tube 14 is slidably mounted the stem 15 of a valve 16 engageable with the seat 11 and normally engaging such seat under the action of a spring 17 encircling the stem 15 between the valve 16 and the confronting end of the guide 14, the guide 14 being provided with openings 19 so that the air may freely escape from the guide in the sliding of the stem 15 within the guide.

In the present instance the lower wall of the valve chamber 12 is formed with an outlet port that is in open communication with an exhaust pipe 18 that discharges into the atmosphere at some suitable point.

25 In the operation of the motor the gases are sucked into the engine cylinders from the carburetor through the chamber 1 and the manifold and as long as the engine operates normally the check valve 6 is held open incident to the continuous suction through the manifold. When, however, a 30 back fire occurs the check valve 6 immediately closes incident to the pressure set up in the manifold and the valve 16 is forced open by such pressure against the action of the spring 17, thereby permitting the gases from 35 the back fire to pass through the tube 9, valve chamber 12 and exhaust pipe 18 to the atmosphere.

40 It will be noted that the spring 17 holds the valve 16 against its seat normally, so that in the normal operation of the engine the manifold is closed to the atmosphere, except for its connection with the carburetor.

From the foregoing description, taken

in connection with the accompanying drawings, it will be seen that I have provided an attachment for internal combustion motors which will effectively prevent disturbance of the carburetor in the event of back fire and which will automatically cut off communication between the carburetor and the engine cylinders and establish communication between the engine cylinders and the atmosphere, so that the gases from the back fire may be discharged into the atmosphere.

45 While I have herein shown and described one preferred form of my invention by way of illustration, I wish it to be understood that I do not limit or confine myself to the precise details of construction herein shown and described, as modifications and variations may be made within the scope of the claim and without departing from the spirit 50 of my invention.

I claim:

55 A device of the class described comprising a chamber adapted for connection in the intake manifold of an internal combustion motor between the cylinders and carburetor, a check valve in said chamber normally operating to permit the passage of gas through 60 said chamber into the motor cylinders and operable to cut off communication between the motor cylinders and carburetor in the event of a back fire, a tube in open communication with said chamber, a check valve 70 normally closing the outer end of said tube and adapted to open to the atmosphere in the event of back fire, a valve chamber surrounding said last mentioned check valve, a 75 guide formed in said valve chamber, a stem for said check valve working within said guide and a spring surrounding said check valve to hold the same normally closed.

80 In testimony whereof, I affix my signature.

WILLIS B. YOUNG.
